UNITED STATES PATENT OFFICE.

EMIL C. BONIGER, OF DAVENPORT, IOWA.

MOLD FOR CONCRETE BLOCKS.

Application filed March 21, 1921. Serial No. 453,885.

To all whom it may concern:

Be it known that I, EMIL C. BONIGER, a citizen of the United States, residing at Davenport, in the county of Scott and State 5 of Iowa, have invented certain new and useful Improvements in Molds for Concrete Blocks, of which the following is a specification.

My invention has reference to molds for 10 concrete blocks, and has for its purpose to assist in the production of building blocks of a novel design, the use of which blocks in a wall will enhance the efficiency and durability thereof. The invention comprises 15 a suitable base, and an outer frame or form supported thereon, which form is divided into a desired number of compartments, each of which is subdivided by a plurality of smaller forms of eccentric shape into spaces 20 for receiving the material from which the blocks are formed. Means are also provided whereby the forms and blocks can be readily separated after the blocks have become sufficiently hard, for the purpose of removing 25 such blocks.

In the drawings:—

Fig. 1 is a plan view of my invention, in its preferred embodiment.

Fig. 2 is a side view thereof.

Fig. 3 is a fragmentary view of the base 30 1, in perspective.

Fig. 4 is a perspective view of one of the forms 11.

Fig. 5 is an end section of one of the partitions 9.

Fig. 6 shows one of the covers 19, in detail.

Fig. 7 is a detached view of one of the posts 5.

Fig. 8 is a similar view of one of the posts 6.

Fig. 9 is an end view of the device.

Fig. 10 shows a series of blocks, such as are produced by the mold, as they appear 45 when in place in a wall.

Fig. 11 is a plan view of a modified arrangement of the invention.

Fig. 12 is an enlarged view of one of the forms 23, removed.

1 represents a base-plate, supported on 50 any desired number of cross-pieces 2, connected with which are sockets 3 and 4, adapted to receive side posts 5 and corner posts 6, against which are supported side- 55 plates 7 and end-plates 8, forming a rectangular frame, which is divided into a series

of longitudinal compartments by means of partitions 9, provided at their ends with lugs 10 for engagement with corresponding perforations in the end plates 8. In each compartment is a plurality of forms 11, of a modified diamond shape, provided at their ends with angular extensions 12, fitted with lugs 13 for engagement with perforations 14 in the partitions 9 and similar openings 15 in the side plates 7. By this means the forms 11 are held in position in spaced-apart relations, producing spaces 16 which are designed to receive the material from which the blocks are formed. At each end of the 70 mold the forms 11 are of irregular shape, and provided with end extensions 17 which are connected with the end-plates 8. This produces angular spaces 18, for the formation of corner-blocks. Each of the forms 11 is fitted with a cover 19, to prevent the material from entering such forms.

In operation, the forms all being in place, as shown in Fig. 1 of the drawings, the mold is filled with a mixture of cement in a semi-liquid state, which mixture finds its way 80 into all parts of the mold except to the interior of the forms 11. This results in the production of a plurality of blocks such as are illustrated at 20 in Fig. 10, with an occasional corner-block 21. When set in a wall, as shown, these blocks will be separated by spaces 22, corresponding in shape 85 with the forms 11. This produces a wall in which the joints are in staggered relation, 90 with the spaces separating them, so that it is a difficult matter for moisture to permeate the wall.

After the mixture has sufficiently hardened the posts 5 and 6 are detached and the 95 side and end plates of the mold removed, whereupon the concrete blocks and forms 11 can be alternately withdrawn.

If desired, the base 1 can be mounted upon a suitable truck, for transportation of the 100 blocks from one point to another, and two or more of the molds can be supported one above the other, and successively filled with the material.

It will be obvious that the opposite faces 105 of the blocks which are produced in the mold will be smooth, on account of such faces being formed against the partitions 9 or side plates of the form, but if it is desired to have a rough finish on one face of 110 the block, this can be accomplished by replacing the forms 11 with forms 23 of simi-

lar shape, but turned edge-wise in the spaces between the partitions, as shown in Fig. 11. The forms 23 have end-pieces 24 similar to the extensions 12 of the forms 11, which 5 act in the same way as separating plates. These forms are provided on their edges with lugs 25, adapted to enter openings in the partitions, and hold the forms in place. A longitudinal sectional view of said forms 10 would be similar in appearance to a single series of the forms 11, as shown in Fig. 1. Both ends of the forms 23 would be closed by the partitions, and the mixture would work down between and beneath such forms, 15 the upper face of each stone being unfinished, and the upper faces of the blocks can be further roughened before hardening, if desired.

What I claim and desire to secure by Letters Patent, is:

1. A device of the class described, com-

prising a frame; and a series of substantially diamond-shaped forms arranged in said frame in spaced-apart overlapping relation, and provided at their ends with oppositely disposed extensions adapted for engagement with said frame. 25

2. A device of the class described, comprising a base; a plurality of posts removably supported at the sides and ends thereof; 30 frame pieces removably supported by said posts, and forming a rectangular mold; partitions removably connected with said frame pieces, and dividing said mold into similar compartments; and a plurality of forms 35 provided with extensions adapted for detachable connection with said partitions and frame pieces; said forms dividing said compartments into irregular spaces of a desired pattern. 40

In testimony whereof I affix my signature.

EMIL C. BONIGER.
